METHOD OF PRODUCING GEARS

Ernest Wildhaber, Brooklyn, N. Y., assignor to
Gleason Works, Rochester, N. Y., a corpora-
tion of New York

Application March 23, 1931, Serial No. 524,633

25 Claims. (Cl. 90—4)

The present invention relates to the production of bevel and hypoid gear pairs of the type where one member of the pair is cut in a forming or non-generating operation and the other member is generated, and the invention relates more particularly to the production of bevel and hypoid gears of this character which have skew or longitudinally curved teeth.

Insofar as this invention relates to the production of hypoid gears, it may be regarded as an improvement over the method of my Patent No. 1,622,555 of March 29, 1927.

Gear pairs in which one member is non-generated can be cut faster and more cheaply than pairs in which both members are generated. A gear can be cut faster if no generating roll is required than if a generating roll must be used, while a gear-generating machine is more complicated in construction and operation than one intended to do form-cutting only. These advantages have been realized for years, yet gear pairs of the character described have never come into use on a commercial scale. Difficulties in production, which will be outlined below, have heretofore more than offset the manifest advantages of this type of gearing.

Bevel and hypoid gears should have teeth tapering in depth from their outer to their inner ends for reasons of mesh, and, also, in order to obtain requisite strength at the small ends of the teeth. Moreover, it is desirable in gear cutting to use straight-sided cutting tools because of their simplicity and the accuracy with which they can be produced and, also, because of the suitable tooth shapes which can be obtained with such tools.

Heretofore when gear pairs were cut in which one member was non-generated, the other member was always generated in an operation in which tool and blank were rolled relative to one another as though the blank were rolling on the mate non-generated gear, the basic theory being that thus the generated member would be conjugate to the non-generated gear and the two would run correctly together. However, when either skew or curved tooth bevel or hypoid gear pairs, containing one non-generated member, were cut in this way with teeth of tapering depth and with straight-sided cutting tools, a highly objectionable bias bearing condition has been obtained. Bias bearing is a tooth bearing or area of tooth surface contact that extends diagonally across the mating side tooth surfaces of a pair. It causes the gears to be noisy and results in uneven distribution of tooth loads. It is due to

mismatch of the pressure angles of mating tooth surfaces of the gears.

To retain the benefits and advantages of the form cutting process and avoid bias bearing, it has been necessary heretofore, either to cut the gear pairs with teeth of parallel depth or with spherical tooth surfaces. Tapered gears which have teeth of parallel depth, that is, of uniform tooth height from end to end are, however, weak at their small ends because, for one reason, the small ends of the teeth are of excessive height in proportion to thickness. Hence, the parallel depth method of cutting has not proved satisfactory for it avoids bias bearing only at the sacrifice of tooth strength. By use of spherical cutters, gears of the character referred to can be cut with teeth of tapering tooth depth and without bias, but this method is restricted to the cutting of longitudinally curved teeth and the tools used must have cutting edges of circular arc profile accurately centered on the axis of rotation of the tool. The spherical cutting method has consequently not proved satisfactory, either, for it avoids bias bearing only at the sacrifice of simplicity.

The purpose of the present invention is to provide a simple method of cutting bevel and hypoid gears of the character referred to with teeth of tapering depth and without bias bearing and while employing straight-sided cutting tools. The new steps involved in the present invention are not limited, however, to cutting with straight-sided cutting tools or, in fact, to cutting teeth of tapering depth.

With the present invention, one member of the pair, preferably the larger member, is form-cut or non-generated as heretofore, but the pinion instead of being generated conjugate to its mate gear is generated conjugate to an imaginary gear differing from the mate in such manner that the pinion will mesh with its mate without bias bearing and still transmit uniform motion.

In the drawings:

Figures 1 and 2 are a sectional view and a bottom plan view, respectively, illustrating diagrammatically the preferred method employed with this invention of cutting the gear or non-generated member of a pair of longitudinally curved tooth bevel or hypoid gears;

Figure 3 is a diagrammatic view, showing the difficulty heretofore experienced in cutting gear pairs of the character referred to with teeth of tapering depth;

Figure 4 is a plan view and Figure 5 a part elevational and part sectional view illustrating

diagrammatically the method of generating, according to this invention, the mating pinion of a hypoid gear pair;

Figures 6 and 7 are corresponding views, illustrating diagrammatically the method of generating, according to this invention, the mating pinion of a bevel gear pair; and

Figure 8 is a diagrammatic plan view illustrating specifically how the opposite sides of the teeth of a longitudinally curved tooth hypoid pinion may be generated, according to a preferred embodiment of the present invention, conjugate to different gears so that when the pinion is in mesh with its mate gear a localized tooth bearing may be obtained.

The invention will, for the sake of illustration, be described in connection with the production of longitudinally curved tooth gears with a face mill cutter, but it applies broadly to gears having longitudinally inclined teeth and is not, of course, limited as to the type of tools employed in the cutting of the gears.

Figures 1 and 2 illustrate the cutting of the non-generated member G of a pair. 10 designates the cutting tool which is a conical face-mill gear cutter having straight-sided cutting edges 11 and 12 inclined to the axis 13 of the cutter in accordance with the pressure angle of the teeth to be cut in the gear blank. In operation, the axis 13 of the cutter is inclined to the axis 14 of the blank so as to cut teeth T in the blank of tapering depth as indicated in Figure 1 and, as in previous methods of cutting these gears, the tooth spaces of the blank are cut by simply feeding the rotary cutting tool 10 into depth. Thus, the tooth surfaces of the gear are exactly complementary to the edges of the cutting tool. No generating roll is employed.

The cutting tool 10 may be a standard face mill gear cutter, in which case the blank will be indexed after the cutting of each tooth space and the tooth spaces of the blank will be completed successively, or it may be a face mill hobbing cutter in which case the blank will have a continuous indexing rotation and all of the tooth spaces of the blank will be operated on simultaneously.

Heretofore, as stated above, the production of gear pairs in which one member is non-generated has always been associated with the idea that the other member should be generated in a process in which the cutting tool represents the mate gear and the tool and blank are rolled together as though the blank were rolling on the mate gear. But, as stated above, this method produces a bias-bearing when the pair is cut tapering depth with straight-sided cutting tools. The reason is obvious: The cutter that cuts the gear must be inclined to the axis of the gear so that its tip surface will sweep out the root surface of the gear, while the cutter which cuts the pinion must represent a tooth of the gear and must, accordingly, be inclined to the axis of the pinion so that its tip surface will represent and sweep out the tip surface of the gear, but the root and tip surfaces of the gear teeth are inclined to one another because the teeth are of tapering depth. Therefore the pressure angles of gear and pinion will not match along the mating tooth surfaces and the condition of bias bearing will be obtained.

Figure 3 illustrates the difficulty resulting from the method of generation heretofore employed, particularly as encountered in the cutting of longitudinally curved tooth bevel and hypoid

gears with straight-sided face mill cutters. This figure is a view of the plane 16 tangent at a mean point of contact O to the mating tooth surfaces of a pair cut according to prior practise and having teeth of tapering depth. 18 denotes a portion of the common pitch line of the mating tooth surfaces. 19 denotes the line of contact between the tangential plane 16 and the conical cutting surface of the gear cutter, while 20 denotes the line of contact between said tangential plane 16 and the conical cutting surface of the pinion cutter. Because the gear and pinion are each cut tapering depth, the two lines 19 and 20 will not coincide but will be inclined at a slight angle to each other, and because of the inclination of the two lines 19 and 20, the conical cutting surfaces of the gear and pinion cutters will not produce matching tooth surfaces on gear and pinion. When a pair was produced according to the prior practise, therefore, with teeth of tapering depth by the use of straight-sided face mill cutting tools, outside of the mean contact point O, the tooth surfaces of gear and pinion were not conjugate.

The mismatch or error was present, also, in varying degrees in longitudinally curved tooth gears of the character described cut with other types of tools and in skew bevel and hypoid gears of the character described, also.

With the method of the present invention, the pinion is generated conjugate to a gear other than its mate and the difference between the mate gear and the gear to which the pinion is generated conjugate is such as to compensate for the mismatch between the tooth surfaces of gear and pinion and enable the pair to be produced with teeth tapering in depth but free of bias bearing.

Figures 4 and 5 illustrate the method of generating a hypoid pinion H according to this invention to mesh with a non-generated gear such as the gear G. The pinion H is generated conjugate to a gear G' different from its mate. The axis of this gear is indicated at 22. Ordinarily the cone radius of the generating gear G' will be different from the cone radius of the mate gear G so that the axis 22 of the generating gear will be offset from the axis 14 of the mate gear, as shown. Ordinarily, too, the axis 25 of the pinion will be offset from the axis 22 of the generating gear G', during generation, a distance Y different from the distance X of offset between the axis of the pinion and the axis 14 of its mate gear G when the two are in mesh. Preferably, however, the axis of the pinion will be inclined to the axis 22 of the generating gear G', during generation, at the same angle as the axis 25 of the pinion is inclined to the axis 14 of its mate gear G when in mesh with the mate gear. In the drawings, this angle is 90°.

The cutter 23 which is employed to generate the tooth surfaces of the pinion represents the imaginary generating gear G' and is positioned with its axis 24 inclined to the axis 25 of the pinion blank to produce teeth of tapering depth in the blank. The cutter has straight sided cutting edges 26 and 27 and may be of standard construction or of the face mill hobbing type.

To generate the tooth surfaces of the pinion H, the cutter 23 is rotated on its axis 24 and simultaneously a relative rolling movement is produced between the cutter and the gear blank H as though the blank were rolling on the gear G'. In this rolling movement, the roll may be divided and the cutter 23 swung about the axis 150

22 of the imaginary generating gear G' while the blank H rotates on its axis 25, or all of the roll may be on the work, in which case, the cutter will be stationary except for its rotation and the blank will both rotate on its axis 25 and be simultaneously swung about the axis 22 of the imaginary generating gear G' or thirdly, all the roll may be on the tool, as will be understood by those skilled in the art.

28 The invention is applicable, also, to the generation of bevel pinions. This is illustrated in Figures 6 and 7. B indicates the bevel pinion blank, and G'' , the gear to which the pinion is generated conjugate. This gear G'' differs from the gear G with which the pinion B is to mate by an amount necessary to compensate for the mismatch of the tooth surfaces of gear and pinion which would otherwise result from the taper in depth of the teeth of the pair when cut with a face mill cutter having straight-sided cutting edges. The axis of the generating gear G'' is indicated at 30 while the axis of the gear with which the pinion B is to mesh is denoted at 31. It will be seen that the axis 30 of the generating gear G'' intersects the axis 32 of the pinion B in a point offset from the apex 33 of the pinion blank.

36 To generate the bevel pinion B to run with a longitudinally curved tooth non-generated gear such as a gear G , a cutter 37 is employed which has straight-sided cutting edges 38 and 39. The axis 40 of this cutter is inclined to the axis 32 of the pinion blank so as to cut teeth of tapering depth in the blank and so as to represent tooth surfaces of the generating gear G'' . The cutter 37 is rotated on its axis 40 and simultaneously a relative rolling movement is produced between the cutter and the pinion blank B as though the pinion blank were rolling on the gear G'' . As 46 before, in this operation the roll may be divided, or all of the roll may be applied to the work or all to the cutter. Preferably the generating gear G'' is so chosen that its axis 30 is inclined to the axis 32 of the pinion at the same angle as the axis 32 of the pinion is inclined to the axis 31 of its mate gear when in mesh. In the drawings, this angle is 90° . It will be understood that a certain amount of liberty may be exercised in the choice of the generating gear, as may be required 50 under varying conditions. Thus the bevel pinion blank B might not only be positioned so that its apex is offset from the axis 30 of the generating gear G'' but, also, so that its axis 32 is offset from the axis 30.

58 The choice of the generating gear G' or G'' for hypoid or bevel pinion generation can be determined mathematically, but is a matter of involved computation. The choice of the generating gear can be determined experimentally in a comparatively simple way. A tool C is first selected (Figure 8) which will produce tooth surfaces of the desired curvature on the pinion blank to mate with the tooth surfaces cut in the mating non-generated gear. This tool is then positioned 66 relative to the pinion blank D as if to represent a tooth side of the mating gear G , namely, a tooth side so positioned that a mean point O in its tooth surface will contact with a corresponding point in the mating tooth surface of the pinion. However, instead of rolling the tool C and pinion blank D relative to one another about the axis 14 of the mate gear G , they are rolled about an axis offset from the axis 14 of the mate gear and corresponding to the axis of a gear 47 to which the pinion D is to be generated conjugate. Usually

the axis of the generating gear is assumed, as at 45 or 46, near the axis 14 and on the line 48 connecting the axis 14 with the mean contact point O .

80 The tool C then represents a tooth side of a gear 47 whose tooth surfaces have contact with the tooth surfaces of the pinion D when rotated at a slightly different ratio from the ratio of rotation of the pinion D with its mate gear G . The roll or angular feed of the cutter C or the gear blank D about the axis of the generating gear 47 is increased over the rotation or angular feed of the gear G in the inverse ratio of the distances of the axis 45 or 46 and the axis 14 from the tooth normal N at the mean contact point O . Under these conditions, tooth contact between the mating tooth surfaces of the gear and pinion at the point O is maintained and uniform motion will be transmitted between the gear and pinion when in mesh.

85 90 95 After generation, the pinion is run with its mate gear to test the tooth contact and it is then determined through visual inspection whether the assumption of the position of the axis 45 or 46 was correct and if not in which direction it was off. If correction is necessary this can be effected easily by recutting the pinion.

100 Where it is desired to top-off and flank-out the tooth profiles of the pinion so as to reduce the area of profile contact or bearing, the axis 45 or 46 may be further displaced along a line 49 or 49', respectively, parallel to the tooth normal N . Ordinarily, however, the axis of the generating gear 47 will be located on the line 48.

110 115 120 125 130 The length of tooth bearing between the tooth surfaces of the pinion and the gear can be controlled in a manner broadly similar to that now practiced in cutting spiral bevel and hypoid gears. Thus, opposite sides of the pinion teeth may be cut conjugate to different generating gears. For instance, the convex sides of the pinion teeth may be cut with a tool having inside cutting edges of a radius less than the radius of the cutting edges of the tool which cut the mating tooth surfaces of the gear, the axis of the generating gear being then located, for instance, at 45. The concave sides of the pinion teeth may then be cut with a cutter having outside cutting edges of increased diameter as compared with the cutting edges of the tool which cuts the mating tooth surfaces of the gear, the axis of the generating gear for these side tooth surfaces being then located, for instance, at 46. This method of cutting will provide a desirable localization of tooth bearing between the mating tooth surfaces of gear and pinion.

135 140 145 While the invention has been described in connection with the production of spiral bevel and hypoid gears and pinions, with a particular type of tool, it is applicable broadly, also, to the production of bevel and hypoid gears having longitudinally inclined teeth, such as skew teeth and the cutting tool employed may be of any type suitable for the cutting of the particular gears which it is desired to produce. In general, the pinion is generated, as described, with tooth surfaces of a lengthwise shape suitable to mesh with the tooth-surfaces of the mate non-generated gear and conjugate to a gear other than its mate to obtain a desirable tooth profile bearing.

150 Thus, while I have described my invention in connection with particular embodiments, it will be understood that the invention is capable of various further modifications and uses and that this application is intended to cover any variations,

uses, or adaptations of the invention, following, in general, the principles of the invention and including such departures from the present disclosure as come within known or customary practice in the gear art and as may be applied to the essential features hereinbefore set forth and as fall within the scope of the invention or the limitations of the appended claims.

Having thus described my invention, what I claim is:

1. The method of producing a pair of tapered gears having teeth of tapering depth which comprises cutting the side tooth surfaces of one member of the pair in a forming operation by a relative depth-wise feed between the cutter and the gear blank, and cutting the side tooth surfaces of the other member of the pair in a generating operation in which the tool represents a tapered gear other than the mate gear and the tool and blank are rolled relative to one another as though the blank were rolling on such a tapered gear.
2. The method of cutting a pair of tapered gears having teeth of tapering depth which comprises cutting the side tooth surfaces of one member of the pair in a forming operation with a straight-sided cutting tool by a relative depth-wise feed between the tool and the blank, and cutting the side tooth surfaces of the other member of the pair in a generating operation also with a straight-sided cutting tool by rolling the tool and blank relative to one another as though the blank were rolling on a tapered gear other than its mate.
3. The method of producing a pair of tapered gears which comprises cutting the side tooth surfaces of one member of the pair by positioning a cutting tool and a gear blank relative to one another so that the tool will cut teeth of tapering depth in the blank and effecting a relative cutting motion between the tool and blank to produce teeth on the blank which are longitudinally inclined to a generatrix of the blank while producing a relative depthwise feed between the tool and blank to cut teeth of the proper depth, and cutting the side tooth surfaces of the other member of the pair by positioning a cutting tool and a gear blank relative to one another so that the second tool will cut teeth of tapering depth in the second blank and effecting a relative cutting motion between the second tool and blank to produce teeth shaped longitudinally to mate with those of the first gear and producing a relative rolling motion between the second tool and blank as though the second blank were rolling with a gear other than its mate to generate the tooth surfaces of the second gear.
4. The method of producing a pair of tapered gears which comprises cutting the side tooth surfaces of one member of the pair by positioning a cutting tool having straight-sided cutting edges relative to a gear blank so that the tool will cut teeth of tapering depth in the blank and effecting a relative cutting movement between the tool and blank to produce teeth on the blank which are longitudinally inclined to a generatrix of the blank while effecting a relative depthwise feed between the tool and blank to cut teeth of the proper depth in the blank, and cutting the side tooth surfaces of the other member of the pair by positioning a cutting tool having straight-sided cutting edges relative to a second gear blank so that the second tool will cut teeth of tapering depth in the second blank, and effecting a relative cutting motion between the second tool and blank

to produce teeth on the second blank which are shaped longitudinally to mesh with those of the first gear and producing a relative rolling motion between the second tool and blank as though the second blank were rolling with a gear other than its mate to generate the tooth surfaces of the second blank.

5. The method of producing a tapered gear suitable to mesh with a non-generated tapered gear having teeth of tapering depth which comprises positioning a cutting tool and a tapered gear blank relative to one another so that the tool will cut teeth of tapering depth on the blank and effecting a relative cutting movement between the tool and blank to produce teeth on the blank which are longitudinally inclined to straight generatrices of the blank, while simultaneously producing a relative rolling motion between the tool and blank as though the blank were rolling on a gear other than its mate.

6. The method of producing a tapered gear suitable to mesh with a non-generated tapered gear having teeth of tapering depth which comprises positioning a cutting tool having straight-sided cutting edges and a tapered gear blank relative to one another so that the tool will cut teeth of tapering depth on the blank and effecting a relative cutting movement between the tool and blank to produce teeth on the blank which are longitudinally inclined to straight generatrices of the blank, while simultaneously producing a relative rolling motion between the tool and blank as though the blank were rolling on a gear other than its mate.

7. The method of producing a tapered gear suitable to mesh with a non-generated tapered gear having teeth of tapering depth which comprises positioning a face mill cutting tool and a tapered gear blank relative to one another so that the tool will cut teeth of tapering depth in the blank and rotating the tool in engagement with the blank while producing a relative rolling motion between the tool and blank as though the blank were rolling on a gear other than its mate.

8. The method of producing a tapered gear suitable to mesh with a non-generated tapered gear having teeth of tapering depth which comprises positioning a face mill cutting tool having straight sided cutting edges and a tapered gear blank relative to one another so that the tool will cut teeth of tapering depth in the blank, and rotating the tool in engagement with the blank while producing a relative rolling motion between the tool and blank as though the blank were rolling on a gear other than its mate.

9. The method of producing a hypoid pinion suitable to mesh with a mating non-generated gear having teeth of tapering depth which comprises positioning a face mill cutting tool and a pinion blank relative to one another so that the tool will cut teeth of tapering depth in the blank, and rotating the tool in engagement with the blank while producing a relative rolling movement between the tool and blank about an axis offset from the axis of the blank a distance different from the offset between the pinion and the mate gear when in mesh.

10. The method of producing a hypoid pinion suitable to mesh with a mating non-generated gear having teeth of tapering depth which comprises positioning a face mill cutting tool having straight-sided cutting edges and a pinion blank relative to one another so that the tool will cut teeth of tapering depth in the blank and rotating the tool in engagement with the blank while pro-

blank while producing a relative rolling motion between the cutter and blank as though the blank were rolling on a gear other than its mate.

20. The method of generating a tapered pinion

25 having longitudinally inclined teeth which comprises cutting its side tooth surfaces by imparting a cutting motion to a cutting tool while simultaneously producing a relative rolling motion between the tool and blank about an axis inclined 80 to the blank axis at an angle equal to the angle 85 between the axes of the pinion and its mate gear, when in mesh, and intersecting the blank axis in a point offset from the blank apex.

21. The method of generating a tapered pinion

25 having longitudinally inclined teeth suitable to mesh with the teeth of a non-generated tapered gear which comprises generating its opposite side tooth surfaces conjugate to different gears, each of which is different from the mate gear.

20 22. The method of generating a tapered gear having longitudinally inclined teeth which comprises cutting one side of its teeth in a generating operation in which the cutting tool and blank are rolled relative to one another about an axis 90 offset from the blank apex but inclined to the axis of the blank at an angle equal to the angle between the axes of the pinion and its mate gear, when in mesh, and cutting the opposite sides of its teeth in a generating operation in which the cutting

25 tool and blank are rolled relative to one another about an axis inclined to the axis of the blank at an angle equal to the angle between the axes of the pinion and its mate gear, when in mesh, but offset a different distance from the apex of the pinion than the axis of roll employed when generating the first-named side of the teeth. 95

23. The method of producing a tapered gear suitable to mesh with a non-generated tapered gear having teeth of tapering depth which com-

40 prises positioning a cutting tool and a tapered gear blank relative to one another so that the tool will cut teeth of tapering depth on the blank and effecting a relative cutting movement between the tool and blank to produce teeth on the blank 100 which are longitudinally inclined to straight generatrices of the blank while simultaneously producing a relative rolling motion between the tool and blank as though the blank were rolling on a gear other than its mate, the axis of the blank 105 being maintained during said rolling motion at
